ADJUSTABLE HEADBAND

Marshall N. Anderson, Chicago, Ill., assignor to
Sellstrom Manufacturing Company, Chicago,
Ill., a corporation of Illinois.

Application May 11, 1945, Serial No. 593,191

11 Claims. (Cl. 2-8)

1

This application relates to adjustable headbands, more particularly to continuously adjustable headbands for welders' helmets and the like, and it is an object of the invention to provide an improved headband of the character indicated.

Headbands for supporting welders' helmets and the like generally comprise a flexible band which is adapted to surround the head of the wearer and to which the helmet or other protecting shield is attached. The flexible band is made adjustable so that the same helmet may be used by persons of different head sizes and so that the band may be worn tightly or loosely on the same person's head. Commonly the adjustable feature is incorporated into the band by overlapping the ends thereof, placing a tubular casing around the overlapping ends and mounting an adjusting knob on the casing for shifting the ends of the band relative to each other to vary its size. The ends of the band are provided with slots having gear racks associated therewith which are brought into juxtaposition inside of the tubular casing, and a pinion gear also inside of the tubular casing is arranged to engage the gear racks, the pinion gear being attached to the adjusting knob for shifting the band ends. Spring detent means are associated with the tubular casing and the adjusting knob whereby the adjusting knob is held in its adjusted position.

In assembling such adjustable bands the band ends must be inserted into the tubular casing and the slots and gear racks must be brought into operative position. Along with this portion of the assembling procedure the pinion gear must be placed in engagement with the gear racks, the adjusting knob must be attached to the pinion gear and to the assembly as a whole by some means, such as a rivet extending from the inside of the tubular casing. This assembling procedure is difficult and time consuming. Accordingly, it is a further object of the invention to provide an adjustable headband of the character indicated which is economical to make, easy to assemble and has relatively few parts.

It is a further object of the invention to provide an adjustable headband of the character indicated in which the operating means are carried solely by the band ends.

In carrying out the invention in one form, an adjustable headband comprising a flexible band adapted to be worn around a user's head is provided. The flexible band has its ends overlapping each other and each of the overlapping ends includes a toothed rack. Constraining means in-

2

cluding depending flanges are provided for the overlapping band ends along with operating means for adjusting the length of the adjustable band, the operating means including gear means associated with the racks. Resilient means are arranged between the operating means and the band ends to bear against one of the band ends and the operating means for restraining movement of the operating means. The depending flanges on the constraining member are adapted to contact the resilient means to prevent movement of the resilient means during adjustment of the band.

For a more complete understanding of the invention, reference should now be had to the accompanying drawing, in which:

Fig. 1 is a rear perspective view of a welder's helmet band embodying the invention;

Fig. 2 is a sectional view taken substantially along the lines 2-2 of Fig. 1;

Fig. 3 is a sectional view taken substantially along the lines 3-3 of Fig. 2;

Fig. 4 is an exploded perspective view showing the relative positions of various elements of the adjustable band;

Fig. 5 is a front elevational view of a modified form of a welder's helmet band embodying the invention; and

Fig. 6 is a sectional view taken substantially along lines 6-6 of Fig. 5.

Referring more particularly to the drawing in which the same reference characters are used to denote corresponding parts in the different figures, the invention is embodied in a headband 10 mounted inside of a welder's helmet or the like 11. The welder's helmet is shown in broken lines and includes a window for protecting the user's eyes while still permitting sufficient illumination to be transmitted for the user to properly envision his work. The headband 10 comprises a flexible band 12 which is relatively circular in form to fit around the user's head and includes a cushioning pad 13, a crossband 14, and means for adjusting the size of the band 12. The crossband 14 is attached to the flexible band 12 at each side thereof by well known means, such as rivets for example, and extends upwardly from the flexible band 12 to form a member which crosses over the head of the user to keep the headband from sliding downwardly too far over the user's head. Adjacent the points where the crossband 14 is attached to the flexible band 12, ears 15 are attached to the crossband 14 and are spaced therefrom at one end as shown. Holes are formed in the spaced away portions of the ears

15 through which holes bolts 16 are received for attaching the helmet 11 or other protecting shield to the headband 10.

The flexible band 12 is a strap of suitable material which, for example, may be metal, fiber, or the like, and is bent into a relatively circular form having the overlapping ends 17 and 18. The overlapping ends 17 and 18 are provided with slots 19 and 20, respectively, the lower edge of the slot 19 being provided with a toothed rack 21 and the upper edge of the slot 20 being provided with a toothed rack 22. In the assembled position of the headband the overlapping ends 17 and 18 lie flat against each other thereby bringing the slots into registry and consequently bringing the toothed racks into position facing each other. A gear 23 is received in the slots 19 and 20 and engages the racks 21 and 22 so that upon rotation of said gear the overlapping ends 17 and 18 will be shifted back and forth relative to each other for adjusting the size of the band. The width of the slots 19 and 20 is substantially the same as the diameter of the gear 23 so that the edges of the slots opposite the gear racks are virtually in contact with the gear 23 thereby preventing relative edgewise movement of the ends 17 and 18. The ends 17 and 18 are held flat against each other by a washer 34 bearing against the rear side of the end 18 and by the spring 37 bearing against the front side of the end 17 and the adjusting knob 33, the assembly being held together by the bolt 35 and the nut 36 as shown.

Associated with the band 12 to keep the band ends 17 and 18 as well as the head of the bolt 35 and the washer 34 out of contact with the user's head is the constraining member or guide 24. The constraining member 24 is curved to fit the user's head, is sufficiently flexible to permit its bending a small amount when the headband is adjusted in size but also is sufficiently rigid to maintain the generally curved shape of the band, and includes a backing or supporting portion 25 from which extend the lateral edges 26 and the depending flanges 27 and 28. The backing member 25 is somewhat wider than the band 12 so that the band ends 17 and 18 fit loosely between the lateral edges 26, and the lateral edges 26 are wider than the thickness of the combined ends 17 and 18 and the washer 34 so that the band ends fit loosely between the backing member 25 and the depending flanges 27 and 28. In the assembled position with the backing member 25 adjacent the rear face of the band end 18, the depending flanges 27 and 28 extend over or embrace a portion of the edges of the band end 17 thereby forming a guide for the band ends in their movement relative to each other. Any tendency on the part of the band ends to become askew by pivoting about the gear 23 is prevented by the lateral edges 26. At the center of the constraining member 24 the flanges 27 and 28 are removed leaving the edges 29, 30, 31 and 32 (Figs. 1 and 5) for a purpose to be described.

The band ends 17 and 18 are shifted relative to each other by turning the adjusting knob 33 which is connected to the pinion gear 23 as shown most clearly in Figs. 2 and 4 and are held in an adjusted position by preventing rotation of the adjusting knob 33 as will be made clear. The adjusting knob 33 has a front portion on which the embossments 38 are formed so that a suitable grip thereon may be obtained, and formed at the rear surface of the adjusting knob is a shoulder or boss 49 in which is formed a series of

radially extending notches or recesses 39 which define a series of protuberances 39a. The notches are arranged to form a complete circle and receive the protuberances or detents on the spring 37 for holding the adjusting knob in any position. The tops of the protuberances 39a are spaced inwardly of the outer extent of the shoulder or boss 49 forming thereby a flange 50. Also extending from the rear of the adjusting knob is the shoulder 48 from which extends the pinion gear 23 and extending through the pinion gear and the adjusting knob proper is a hole through which the bolt 35 is received, the rear portion of the hole being conical in form to receive a similar conical portion in the washer 34 for a purpose to be described. While the gear 23 is shown as being an integral portion of the adjusting knob 33 it will be clear that the gear may be separately formed and attached to the adjusting knob.

The spring member 37 is interposed between the band end 17 and the adjusting knob 33 for providing some support for the adjusting knob as well as for restraining rotation thereof. It includes two end members 40 and 41 and a body portion 43. The end members 40 and 41 are each provided with lugs 42 at the ends thereof and are curved outwardly so that the ends adjacent the lugs 42 are the only points of contact of the end members with the band 17 (Figs. 2 and 6) thereby reducing the area of frictional contact to a minimum. The end members 40 and 41 are of sufficient length between the lugs 42 to loosely fit into the interrupted portion of the flanges 27 and 28, and the width of the spring 37 between the end members 40 and 41 is such that the members 40 and 41 are received between the interrupted flanges with the lugs 42 lying adjacent the edges 29, 30, 31 and 32. Between the end members 40 and 41 of the spring 37 is the body portion 43 which has reduced portions at its junction with the end members and has an enlarged portion extending from the junctions, the maximum dimension of the enlarged portion being somewhat smaller than the inside diameter of the flange 50. The enlarged portion is curved outwardly from its junction with the end members, and midway between the end members at the position of maximum outward curvature the protuberances or detents 44 and 45 are formed at points diametrically opposite each other. The protuberances 44 and 45 are adapted to lie in the notches 39 between the radial projections 39a in the adjusting knob 33 and thereby engage the radial projections 39a to resist or restrain movement of the adjusting knob for retaining the adjustment of the band 12. The curved end portions 40 and 41 are resilient and the curved body 43 is resilient. The curved body 43 joins the curved ends at their point of maximum curvature and hence the two curvatures combine to effect a greater resilience in the spring 37 for urging the detents into holding position. The spring member 37 is provided with a central opening 46 somewhat larger in diameter than the diameter of the shoulder 48 through which the gear member 23 is adapted to pass and the detents 44 and 45 are spaced relatively far apart so as to provide support for the adjusting knob.

The described elements are assembled for operation substantially as follows: Assuming that the flexible band 12 is bent into a substantially circular form with the crossband 14 attached thereto, the end member 18 is inserted into the constraining member 24 from one end with the bolt 35 having the washer 34 assembled thereto

extending through the slot 20 of the band end 18 and between the flanges 21 and 23. The end 17 is now inserted into the constraining member 24 from the opposite end so that it lies outwardly of the end 18 and is brought out from the constraining member between the edges 29 and 30 and 31 and 32 of the interrupted portion of the flanges 21 and 23 to extend a sufficient distance so that the bolt 35 will pass underneath the end 17 to extend through the slot 19. After this the end 17 is pushed back to lie between the edges 29 and 30 and 31 and 32 and the end 17 is then pushed further through the constraining member 24 until it occupies the position shown in Fig. 1. The parts are now arranged so that the bolt 35 lies approximately centrally between the edges 29, 30, 31 and 32 and the end edges of the band ends 17 and 18 are approximately equally spaced from the bolt 35. The spring 37 is then placed so that the spring ends 40 and 41 are received between the interrupted portions of the flanges 21 and 23 with the bolt 35 extending through the opening 46 in the spring. The adjusting knob 33 with the operating gear 23 is assembled to the structure by pushing the adjusting knob 33 onto the extending bolt 35 whereupon the gear 23 passes through the superimposed slots 19 and 29, the teeth of the gear 23 engage the gear racks 21 and 22, the detents 44 and 45 are received in the spaces 39 between the protuberances 39a, the shoulder 43 of the adjusting knob is received in the opening 46 and the edge of the body member 43 adjacent the protuberances is received within the flange 59. To complete the assembly lock washer 47 is placed over the bolt 35 and the nut 36 is screwed thereto. The head of the bolt 35 is conical in form so as to be received in nesting relationship in the conical portion of the washer 34 and the conical portion of the washer is received in the conical portion of the hole through the gear 23. The head of the bolt is also curved in form as shown so that in the assembled position the head of the bolt protrudes outwardly from the rear surface of the washer. The workman assembling the band by pressing against the rear surface 25 of the constraining member 24 presses against the head of the bolt and produces sufficient friction to keep the bolt from turning so that the nut 36 can be joined to the bolt in a satisfactory manner without having the bolt slip. The band ends 17 and 18 are loosely received in the constraining member 24 and the operating structure including the gear 23, the adjusting knob 33, the spring 37, the washer 34 and the bolt and nut 35 and 36 are supported by the band ends.

In order to adjust the band 12 to any desired size the adjusting knob 33 is turned thereby turning the gear 23 which through engagement with the racks 21 and 22 moves the band ends outwardly or inwardly. Any effort to turn the knob 33 tends to rotate the spring 37 since the detent members 44 and 45 are engaged by the protuberances 39a. Rotating movement of the spring 37 beyond the slight initial rotation as well as translational movement is prevented since the lugs 42 engage the edges 30 and 31 or 29 and 32, depending on the direction of rotation of the knob 33 whereupon rotating the adjusting knob forces the detents 44 and 45 out of the spaces 39 between the protuberances 39a. Preventing translation of the spring 37 causes the adjusting knob 33 to remain in its centered position between the edges 29, 30, 31 and 32 since translational movement of the adjusting knob brings

the shoulder 43 into contact with the edge of the hole 46. The resiliency of the spring 37 keeps the detents 44 and 45 in the recesses 39 at all times so that the adjusting knob is held in its adjusted position until force is exerted thereon to turn it.

In Figs. 5 and 6 in which the same reference characters are used as in Figs. 1-4 for corresponding elements, a modified form of the invention is shown in which one of the band ends is stationary and the adjusting is produced by moving the other band end. Two band ends 51 and 52 of a flexible band corresponding to the flexible band 12 are brought into overlapping relationship with each other inside of the constraining member 24. The band end 52 is similar to the band end 17 in that it includes a slot 53 having gear rack 54 arranged at one edge of the slot. The band end 51 differs from the band end 18 in having a series of three circular holes 55 which are of a slightly larger diameter than the gear 23. In other particulars the embodiment shown in Figs. 5 and 6 is similar to those of the embodiment of Figs. 1-4. The second embodiment is assembled in substantially the same manner as the first embodiment so that the gear 23 is received in one of the circular holes 55 in the band end 51 and thereby fixing it in a stationary position. Fixing the band end 51 as described produces the general head size desired. That is if a large head size is desired the gear 23 is fitted into the hole adjacent the end of the band and if a small head size is desired the gear 23 is placed in the hole farthest from the end. After the desired head size has been selected the headband is adjusted by rotating the adjusting knob 33 whereby the band end 52 is moved while the band end 51 remains stationary.

By providing a series of spaced holes 55 in the headband, another advantage is attained, namely, that of allowing the band to be shifted in the event of wearing out of the teeth of rack 54 engaged with pinion or gear 23, so as to present another portion of the rack for engagement with the said gear. The life of the helmet is thus increased.

While particular embodiments of the invention have been shown it will be understood, of course, that the invention is not limited thereto since many modifications may be made, and it is, therefore, contemplated by the appended claims to cover any such modifications as come within the true spirit and scope of the invention.

Having thus described the invention, what is claimed and desired to be secured by Letters Patent is:

1. An adjustable headband comprising a flexible band adapted to be worn around a user's head having a pair of overlapping ends, each of said overlapping ends including a toothed rack, guide means for said overlapping ends, operating means including gear means associated with said toothed racks for adjusting the length of said band, and resilient means for restraining movement of said operating means, abutting means integral with said guide means for engagement by said resilient means to prevent rotation of said resilient means, said resilient means and said operating means being carried by said overlapping ends independently of said guide means.

2. An adjustable headband comprising a flexible band adapted to be worn around a user's head having a pair of overlapping ends, each of said overlapping ends including a toothed

rack, constraining means including depending flanges for said overlapping ends, operating means including gear means associated with said racks for adjusting the length of said band, and resilient means bearing against one of said bands and said operating means for restraining movement of said operating means, said depending flanges being adapted to contact said resilient means to prevent movement of said resilient means during adjustment of said band.

3. An adjustable headband comprising a flexible band adapted to be worn around a user's head having a pair of overlapping ends, each of said overlapping ends including a toothed rack, constraining means for said band ends having a backing member adapted to lie adjacent the band ends on the inside thereof and flanges depending from said backing member and overlying said band ends on the outside thereof, operating means including gear means for adjusting the length of said band, and resilient means bearing against one of said bands having projections engaging said operating means for restraining movement thereof, said resilient means having edges adapted to bear against said depending flanges for preventing rotation of said resilient means during adjustment of said band.

4. An adjustable headband comprising a flexible band adapted to be worn around a user's head having a pair of overlapping ends, each of said overlapping ends including a toothed rack, constraining means for said band ends having a backing member adapted to lie adjacent the band ends on the inside thereof and flanges depending from said backing member and adapted to overlie said band ends on the outside thereof, said depending flanges including interrupted portions, operating means including gear means for adjusting the length of said band, and resilient means having protuberances engaging said operating means, said resilient means including a plurality of bearing members received between said interrupted flanges and bearing against one of said band ends.

5. An adjustable headband comprising a flexible band adapted to be worn around a user's head having a pair of overlapping ends, at least one of said overlapping ends including a toothed rack, constraining means including depending flanges for said overlapping ends, operating means including gear means associated with said rack for adjusting the length of said band, and resilient means bearing against one of said bands and said operating means for restraining movement of said operating means, said depending flanges being adapted to contact said resilient means to prevent movement of said resilient means during adjustment of said band.

6. An adjustable headband comprising a flexible band adapted to be worn around a user's head having ends overlapping each other whereby one of said ends lies outwardly of the other, at least one of said overlapping ends including a toothed rack, guide means for said overlapping ends, operating means including gear means associated with said toothed rack for adjusting the length of said band, said guide means having exposed edges adjacent said operating means, and resilient means bearing against said outwardly lying one of said overlapping ends and said operating means for restraining movement of said operating means, said exposed edges being adapted to contact said resilient means to prevent rotational movement of said resilient means during adjustment of said band.

7. An adjustable headband comprising a flexible band adapted to be worn around a user's head having a pair of ends overlapping each other, one of said ends including a toothed rack and the other of said ends including an opening, guide means for said overlapping ends, gear means extending through said opening and engaging said toothed rack, operating means for said gear means, said guide means having exposed edges adjacent said operating means, and resilient means bearing against one of said bands and said operating means for restraining movement of said operating means, said exposed edges being adapted to contact said resilient means to prevent rotational movement of said resilient means during adjustment of said band.

8. An adjustable headband comprising a flexible band adapted to be worn around a user's head having a pair of overlapping ends, one of said ends including a toothed rack and the other of said ends including an opening, constraining means for said band ends having a backing member adapted to lie adjacent the band ends on the inside thereof and flanges depending from said backing member, and adapted to overlie said band ends on the outside thereof, said depending flanges including interrupted portions, operating means including gear means extending through said opening and engaging said rack for adjusting the length of said band, and resilient means having protuberances engaging said operating means, said resilient means including a plurality of bearing members received between said interrupted flanges and bearing against one of said band ends.

9. An adjustable headband comprising a flexible band adapted to be worn around a user's head having a pair of overlapping ends, one of said ends including a toothed rack and the other of said ends including a series of openings, constraining means for said band ends having a backing member adapted to lie adjacent the band ends on the inside thereof and flanges depending from said backing member and adapted to overlie said band ends on the outside thereof, said depending flanges including interrupted portions, operating means including gear means extending through one of said series of said openings and engaging said rack for adjusting the length of said band, and resilient means having protuberances engaging said operating means, said resilient means including a plurality of bearing members received between said interrupted flanges and bearing against one of said band ends.

10. An adjustable band forming a closed loop comprising a flexible band having a pair of overlapping ends, at least one of said overlapping ends including a toothed rack, guide means for said overlapping ends, operating means including gear means associated with said toothed rack for adjusting the length of said band, and resilient means for restraining movement of said operating means, abutting means integral with said guide means for engagement by said resilient means to prevent rotation of said resilient means, said resilient means and said operating means being carried by said overlapping ends independently of said guide means.

11. An adjustable band forming a closed loop comprising a flexible band having a pair of overlapping ends, each of said overlapping ends including a toothed rack, guide means for said overlapping ends, an operating knob for adjusting the length of said band, gear means extend-

ing from the rear of said knob and movable therewith, said gear means extending past said overlapping ends and having the gear means in engagement with said toothed racks, means attached to said knob engaging the inside surface of the inside one of said overlapping ends, and spring means having one part engaging said knob and having another part engaging and exerting a constant force against the outer surface of the outer one of said bands, said attached 10 means and said spring means providing lateral support of said knob.
